FURNACE CONSTRUCTION

James J. Ward, St. Louis, Mo.

Application May 22, 1933, Serial No. 672,213

3 Claims. (Cl. 110—24)

The invention has among its objects, the production of a device adapted to be placed within the firebox of a furnace, and which will increase the efficiency of combustion therein, which shall be neat and simple in construction, easily installed and removed, economical, sturdy and long-lasting, reliable, satisfactory and efficient for use wherever deemed applicable.

One of the objects of my invention is to provide a member for positioning within the firebox of a furnace, adjacently below the coal-intake opening, and which will form a support for receiving the said fuel, said member being inclined rearwardly and downwardly so that said green coal 10 may be easily moved further rearwardly to the old fuel bed as it burns. Unless the old fuel is pushed back into the firebox, and the green coal placed adjacent the front, inefficient combustion takes place, not only decreasing the effectiveness 15 of such firing, but also increasing the percentage of smoking of the furnace, and hence, with loss in economy of operation.

My invention has among its further objects, the production of a member of the kind described, 20 and which when placed within a firebox in an up-draft furnace, insures that the ignition of the fuel will take place adjacent the top of the coal, instead of adjacent the bottom of the same, in accordance with good engineering precept.

Another object of my invention is to provide a member of the kind set forth, in which the same is made in a plurality of mating sections easily set in place in operative position within the firebox, and similarly easily collapsed or telescoped 30 for removal from the same for replacements or for any other causes.

Many other objects and advantages of the construction herein shown and described, and the uses mentioned, will be obvious to those skilled 40 in the art to which this invention appertains, from the disclosures herein given.

To this end, my invention consists in the novel construction, arrangement, and combination of parts herein shown and described, and the uses 45 mentioned, as will be more particularly pointed out in the claims.

In the drawing, wherein like reference characters indicate like or corresponding parts throughout the views,

Figure 1 is a horizontal cross-sectional view through the firebox of a furnace, in which my invention is shown;

Figure 2 is a vertical cross-section there-through, taken substantially along the line 2—2 of Fig. 1; and

Figure 3 is a perspective detail of the sectional member.

Referring more particularly to the drawing, wherein I have illustrated one of the preferred embodiments of my invention, there is shown a portion of a furnace of any size, shape and material, the same not forming a part of my invention, the firebox of the same being represented generally at A, the grate bars at B and upon which the fuel bed forms as is customary, and the coal feeding opening C.

It is usual good firing practice to push the old coal backwardly to the rear of the firebox before feeding the fresh or "green" coal into the front of the firebox, but even so, there is apt to be some ignition of the fresh fuel taking place adjacent the front of the furnace too quickly for efficient burning, and the path of the draft is upwardly through the fresh fuel-bed as well as the old fuel-bed.

In order to block off the path of the draft in those portions found undesirable, and to insure that the fresh fuel will be ignited only adjacent the top of the fresh fuel bed and just about at that portion which adjoins the old fuel, I have provided a member adapted to be inserted into the fire-box, said member consisting of the pair of mating sections 1 and 2 telescopically interconnected so as to be adjustable for overall length, as by means of the cooperating tongue and groove 3 and 4, respectively, shown.

Trunnions 5 provide end bearings for the sections 1 and 2, to be received within suitable openings or pockets provided through the wall of the firebox, the front edge of the member being of a contour substantially similar to that of the front of the fire-box, as at 6, the same being arcuate in the form shown in the drawing. Said front edge 6 of the member rests or bears against the adjacent surface of the firebox wall and substantially seals the same against draft passage therealong.

Flat wedge elements 7 and 8 are dovetailed into place between the spaces between the sections 1 and 2, at top and bottom thereof, so as to substantially close said spaces thereacross, and further to force said sections into firm engagement at either end, with the firebox, and thus retain the sections in position therein. Removal may be had simply by knocking out the wedges, and then moving the sections together and out of the firebox.

The sections are so proportioned that the arcuate front edge 6 will rest against the surface of the firebox adjacent thereto, to effectually seal

the same against draft leakage to large degree thereat, and so that the top surface of the sections will be inclined downwardly and rearwardly of the firebox, somewhat as shown. In this manner, the fresh coal may be dumped onto the member, a portion of the same feeding down on the inclined surface to adjacent the old coal which has been previously pushed back, and the remainder remaining thereon until it is pushed back subsequently when a fresh supply is to be fed into the firebox.

The draft will not go upwardly in front of the sections 1 and 2, as the same is substantially blocked thereat, and the fresh coal will therefore be ignited at the top of its depth or body, which has been found to be the most efficient manner of firing coal in a furnace of the up-draft type.

Ribs 9 may be provided on the sections 1 and 2 to reinforce the same against warping, especially in those instances where the firebox is rather wide at the front, although they may be dispensed with for small or average sized fireboxes.

What I claim as new and desire to secure by Letters Patent is:

25 1. A plate member of the kind described, comprising a pair of mating sections insertible into the firebox of a furnace and to receive the charge of coal thereon, said sections engaging the front

of the firebox to substantially shut off the draft therealong, and means pressing said sections laterally apart for removably wedging said sections in place in said firebox.

2. In combination with the firebox of an up-draft furnace having a grate, a pair of plate sections within said firebox above said grate and having mating tongue and groove ends for telescopic adjustment, the opposite ends of said plate sections being engageable with the firebox wall, and wedge elements slidably movable between the adjoined ends of said sections to force the sections laterally outwardly simultaneously into firm engagement with the firebox.

3. The combination with a furnace having a grate and a firebox thereabove and with sockets in the side wall of said firebox, of a pair of plates within said firebox above said grate and with trunnions at their outer ends to engage within said sockets, the adjacent ends of said plates being cooperatively tongue and grooved below the top surface of the plates for telescopic adjustment of the latter, and a wedge between said last-mentioned ends above said tongue and groove and flush with said top surface of the plates to spread said plates apart to force said trunnions into firm engagement with said sockets.

JAMES J. WARD.
